(57) **CLAIM**

I claim the ornamental design for a swim goggle with timer,
as shown and described.

DESCRIPTION

FIG. 1 is a front top perspective view of a swim goggle with timer according to the present invention;

FIG. 2 is a front elevation view thereof;

FIG. 3 is a top view thereof;

FIG. 4 is a rear elevation view thereof;

FIG. 5 is a bottom view thereof

FIG. 6 is a left side elevation view thereof; and,

FIG. 7 is a right side elevation view thereof.
